CLAIM

I claim the ornamental design for a triple cup carrier, as shown and described.

DESCRIPTION

FIG. 1 is an isometric view of a triple cup carrier of my new design shown in a folded configuration with a handle portion arranged in a transverse direction to a cup holding portion; FIG. 2 is a right side elevation view of the triple cup carrier thereof;

FIG. 3 is a front elevation view of the triple cup carrier thereof;

FIG. 4 is a rear elevation view of the triple cup carrier thereof;

FIG. 5 is a top plan view of the triple cup carrier thereof; and,

FIG. 6 is bottom view of the triple cup carrier thereof. The broken lines in the form of a cup depicts environmental subject matter and form no part of the claimed design.
